The ornamental design for a battery, as shown and described.

DESCRIPTION

FIG. 1 is a front isometric view of a battery, showing our new design;

FIG. 2 is a rear isometric view of the battery of FIG. 1; FIG. 3 is a front elevation view of the of the battery of FIG. 1;

FIG. 4 is a rear elevation view of the of the battery of FIG. 1;

FIG. 5 is a top plan view of the battery of FIG. 1;

FIG. 6 is a bottom plan view of the battery of FIG. 1; FIG. 7 is a first side elevation view of the battery of FIG. 1; and,

FIG. 8 is a second side elevation view of the battery of FIG. 1.

The dot-dash broken lines included in FIGS. 1 and 3 represent a boundary to the claimed design and form no part thereof.

In the drawings, the broken lines represent portions of the article which form no part of the claimed design.
